[57] CLAIM

The ornamental design for a foldable stand for two guitars, as shown and described.

DESCRIPTION

FIG. 1 is a perspective view of a foldable stand for two guitars, the broken line showing of the guitars is for illustrative purposes only and forms no part of the design;

FIG. 2 is a front elevational view of the stand shown on a reduced scale;

FIG. 3 is a right side elevational view of FIG. 2, the left side elevational view being a mirror image;

FIG. 4 is a rear elevational view of FIG. 2;

FIG. 5 is a top view of FIG. 2;

FIG. 6 is a rear view of the stand in FIG. 2 in folded position; and,

FIG. 7 is a right side view of FIG. 6.
